ATTORNEY.

UNITED STATES PATENT OFFICE

OLE R. EIDE, OF ST. PAUL, MINNESOTA

MORTAR JOINT OR SEAM FILLER

Application filed June 21, 1929. Serial No. 372,620.

My invention relates to a mortar joint or seam filler device designed to facilitate the finishing of stone or brick walls and the main object is to provide a simple, efficient and inexpensive device for said purpose. This object and features of my invention are hereinafter fully set forth, reference being had to the accompanying drawing, in which,—

Fig. 1 is a top view of my device including 10 a gage clip used on its front end when filling vertical seams of walls.

Fig. 2 is a side elevation of Fig. 1 and Fig. 3 is a front end elevation of the device.

Fig. 4 is a side elevation of the device in 15 upright position and its rear part expanded or spread open for the purpose of pouring a quantity of mortar into it.

Fig. 5 is a perspective view of the gage 20 clip 25 of my device.

Fig. 6 is a face view of a position of a brick 25 wall showing the seams to be filled or finished with my improved device.

Referring to the drawing by reference numerals, my device comprises an elongated 25 back or base board 10 and a corresponding but shorter pressure board 11 and between said two boards is provided, on three sides, front and two opposite sides, a continuous flexible wall 12 with corresponding flanged 30 edges 12E suitably fixed to the side edges of the adjacent faces of said boards and to the front edge part of board 11 (see Figs. 1, 2, 3 and 4).

The lower front part of said wall material 35 12 is not, however, fixed to board 10 but forms an inverted U-shaped, forwardly directed opening adapted to be fixed exteriorly of and on the rear part of a flat-mouthed outlet spout 14—15 by suitable means such as a 40 metal band 13. The mouth of said spout comprises a transverse opening forward of base 10, said opening being adjustable for suitable outlet width of mortar desired to fill the seams of a wall and designated as 16.

The spout comprises a sheet metal plate 15 fixed on front end of base 10 and having two parallel upright flanges 15F near its opposite side edges. The other part 14 of the spout has corresponding downward side flanges 50 14F (Fig. 3) adapted to oscillate each par-

allel and close to a flange 15F and the means for oscillating member 14 comprises a pair of side ears 14E each with an aperture for a stud 17 to project through, said stud being suitably fixed in base 10. On each stud 17 above its ear 14E is a thumb screw 19 adapted to be adjusted downwardly against the action of a compression coil spring 18 between each ear and the base 10. Thus it will be readily understood that the opening 16 may be any thickness desired within the limits of adjustment by the thumb screws 19.

The flexible wall 12 is preferably a heavy rubberized canvas or other suitable fabric.

For a clear understanding of the use of 65 my device it will first be stated that a quantity of mortar of suitable consistency is first poured into the rear open end of the device, as at arrow 20, assuming that the device has first been set in upright position as in Fig. 4 70 and the boards 10—11 spread from each other as far as possible.

After filling in mortar as to level 21, (Fig. 4) the adjacent rear ends of boards 10—11 are pressed toward each other to close 75 the rear end of the device and the said end parts may then be clamped together by any suitable means such as the hinged spring jaw-clamp 22 of shallow U-shaped arranged to clamp the closed ends of 10—11 as in Fig. 2. 80 The clamp 22 is shown hinged to member 11 and may have an inward curvature as 22C to engage in a grooved part 10C of base board 10. Obviously when the device is partly filled with mortar and the rear part of the device is 85 closed as described the front end of board 11 will be forced to spread away from board 10 (see Fig. 2) because of said mortar therein.

The operator then grasps the device on both 90 sides, at the middle, with his fingers under board 10 and his thumbs engaging on top of board 11, then holding the spout parallel to a wall seam 23 (as in a wall 24) and exerting pressure on board 11 with his thumbs the device acts as a bellows, forcing mortar 95 from the spout into the wall seams filling them as the operator moves along the seam, assuming such seams to be continuous, as those shown horizontal in Fig. 6. In a preferred size of my device the spout opening 16 100

is too long for proper filling of vertical seams 23, the latter in brick walls being only about 2 inches long. My device is useful also for such vertical seams, as I have provided a 5 spring sheet-metal clip 25 for this purpose, said clip being of U-shape in cross section and adapted to be slipped on the outlet of my device and retained thereon frictionally.

The clip must be of such length as to shut 10 off outlet of mortar from the spout except for an opening sufficient to permit outlet of mortar sufficient to fill a vertical seam 23 as between two aligned bricks, said opening being as between lines A—B of Fig. 1. In filling 15 vertical seams as described the device must be held in such position that its elongated spout opening is in vertical plane.

The operation and construction of my device in a preferred form have been fully disclosed. It is obvious that a number of details 20 of construction may be embodied without departing from the scope and spirit of the invention. For example, the closing means for the rear end of the device may comprise other 25 mechanical means, and the thumb screws 19 may be of such construction as to positively engage and raise or lower the spout section 14 as desired without the use of compression springs 18. The main body of my device is as mentioned a bellows structure but used to squeeze mortar from its normally widest end while its opposite end is closed.

I claim:

1. In a mortar filling device of the class 35 described, a pair of elongated normally parallel board members alined at one end and one of said members shorter than the other, a metal outlet spout mounted on the longer board beyond the other end of the adjacent 40 shorter board, said spout having an outlet transversely of the board and parallel to and outwardly of the forward end of said board, a flexible wall member connecting to the adjacent parts of said boards at their side edges 45 and having a forwardly directed opening arranged to communicate with the rear part of said spout.

2. The structure specified in claim 1, and 50 said spout comprising a fixed flat plate part secured on the longer board and an upper part with a plate parallel to said fixed plate and means for adjusting said upper plate with relation to the fixed plate for selective amount of opening therebetween, and means 55 for shutting off a portion of said variable opening.

3. The structure specified in claim 1, and 60 said spout comprising a fixed flat plate part secured on the longer board and an upper part with a plate parallel to said fixed plate and means for adjusting said upper plate with relation to the fixed plate for selective amount of opening therebetween, and means 65 for shutting off a portion of said variable opening comprising a sheet metal clip of

predetermined length and of U-shape in cross section, said clip adapted to be slipped over the spout opening and frictionally engage same.

4. In a mortar filling device of the class 70 described, a pair of elongated normally parallel board members alined at one end and one of said members shorter than the other, a metal outlet spout mounted on the longer board beyond the other end of the adjacent 75 shorter board, said spout having an outlet transversely of the board and parallel to and outwardly of the forward end of said board, a flexible wall member connecting to the adjacent 80 parts of said boards at their side edges and having a forwardly directed opening arranged to communicate with the rear part of said spout and means for closing the adjacent rear end parts of said board members toward each other and holding them closed 85 for the purpose set forth.

5. A mortar joint and seam filler comprising 90 an elongated rigid base member, a spout mounted at the front end thereof and having an outlet transversely of the said base beyond its front end, an elongated pressure member shorter than the base member and normally in spaced relation to the latter and both said members connected with their rear ends in common plane with the front end of 95 the compression member in spaced relation rearwardly of the said spout; means for holding said rear end parts clamped toward each other, the means for connecting said members comprising integral flexible side and front 100 walls, said front wall provided with an outlet part securable to the rearwardly opening part of said spout, said rear end closing means adapted to be released to permit spreading of said base and compression members, for the purpose described.

In testimony whereof I affix my signature.
OLE R. EIDE.
